UNITED STATES PATENT OFFICE

99,404

DESIGN FOR A GLOVE

Charles R. Kovar, Richmond Hill, N. Y.

Application November 14, 1935, Serial No. 59,555

Term of patent 3½ years

To all whom it may concern:

Be it known that I, Charles R. Kovar, a citizen of the United States, residing at 102-32 Park Lane South, Richmond Hill, Long Island, in the city of New York, county of Queens, and State of New York, have invented a new, original, and ornamental Design for a Glove, of which the following is a specification, reference being had to the accompanying drawing, forming part thereof.

Figures 1 and 2 of the drawing are respectively front and back views of a glove showing my new design.

The entire exposed surface of the glove has the appearance of open mesh knitted fabric. The design is further characterized by lines of embroidered stitching as shown.

I claim:

The ornamental design for a glove, as shown and described.

CHARLES R. KOVAR.
